UNITED STATES PATENT OFFICE.

ROBERT D. BRADLEY, OF BALTIMORE, MARYLAND.

DESIGN FOR AN ADVERTISING-COLUMN.

SPECIFICATION forming part of Design No. 14,137, dated July 31, 1883.

Application filed May 31, 1883. Term of patent 7 years.

To all whom it may concern:

Be it known that I, ROBERT D. BRADLEY, a citizen of the United States, residing in Baltimore, in the State of Maryland, have invented and produced a new and original Design for Advertising-Columns, of which the following is a specification, reference being had to the accompanying engraving, forming a part hereof, and which shows the advertising-column in perspective.

The column consists, essentially, of two parts—viz., a shaft representative of the Egyptian obelisk recently erected in the city of New York, and a polygonal paneled base of larger transverse area for advertising purposes. The shaft has symbols or hieroglyphics thereon corresponding as nearly as possible to those found on the obelisk, and it is supported by a po-

lygonal base which is paneled and used as an advertising medium. Between the base and the shaft is a coping, on which is inscribed information relating to the obelisk and other subjects, and it may have also a thermometer, barometer, and other like instruments; but these are not absolutely essential. 25

I claim as my invention—

The design for an advertising-column shown and described, the same consisting of a representation of the Egyptian obelisk, before referred to, and a polygonal paneled base of 30 larger transverse area.

ROBERT D. BRADLEY.
